UNITED STATES PATENT OFFICE.

HENRY KÜNTZLER, OF KINGSTON, PENNSYLVANIA, ASSIGNOR, BY MESNE ASSIGNMENTS, TO ADDER MACHINE COMPANY, A CORPORATION OF PENNSYLVANIA.

CRANK DRIVING MECHANISM FOR ADDING-MACHINES.

1,080,515.

Specification of Letters Patent.

Patented Dec. 2, 1913.

Application filed June 30, 1908. Serial No. 441,218.

To all whom it may concern:

Be it known that I, HENRY KÜNTZLER, a citizen of the United States, and resident of Kingston, Luzerne county, Pennsylvania, 5 have invented certain new and useful Improvements in Crank Driving Mechanism for Adding-Machines, of which the following is a specification.

My invention relates to a locking mechanism for motor actuating devices for adding machines.

In the following specification the invention is shown and described as applied to the Wales adding machine and to a peculiar driving mechanism attached thereto, but it will be understood that it is equally applicable to other forms of driving mechanism and power transmitting devices, or other adding machines. The power transmitting 20 mechanism referred to is described and claimed in Letters Patent of the United States No. 902,103, issued Oct. 28, 1908, to Charles N. McFarland, and, in brief, comprises a continuously rotating drum actuated by a motor, a counter or intermediate shaft on which the drum is loosely mounted to revolve, a carrier rigidly mounted on the shaft, a control ring mounted to rotate on the shaft and provided with projecting toes, 30 a driving arm eccentrically mounted on the carrier, means for placing a constant tension on the driving arm, a holder adapted normally to keep the driving arm out of contact with the revolving drum inside of 35 which the carrier is mounted, and means for interrupting the function of such holder, comprising a depressible key or actuating bar and means also whereby the function of the holder may be automatically restored.

40 The purpose of this invention is to provide means for locking the actuating device of the power transmitting mechanism and preventing its accidental movement before the cycle of operations governed by it is completed.

45 In the drawings, Figure 1 is a side elevation of a portion of an adding machine and connected mechanism embodying my invention; Fig. 2 is a view similar to Fig. 1 showing the parts in different positions, and Fig. 50 3 is a front view of the parts shown in Fig. 1 partly in section, and Fig. 4 is a side elevation partly in section of the clutch mechanism.

55 Referring to the drawings, 1 is the base of

an adding machine and 2 is a part of one of its side frames of which there are two, one on each side of the machine; 3 is an operating rock shaft by the oscillation of which the mechanism of the adding machine is 60 actuated. Secured to this shaft 3 is a sector 4 having a stop foot 5 to limit its movement in one direction. A link 6 pivoted to the sector at 7 has a lower extension 8 provided with a slot 9 adapted to engage with a wrist 65 pin 10 of a crank 11 secured to an intermediate shaft 105 moved from the power transmitting mechanism.

Mounted on a pair of elbow levers 20 which move together is a depressible actuator bar 21 adapted to move vertically. The levers are adapted to swing on pivots 22, projecting from the frame 2 of the machine. At their lower extremities they are coupled by a link 23 so that they will move together 75 and to one of them at 24 is pivoted a link 25 which in turn is pivoted to a crank 26 rigidly secured to a rock shaft 27, to the other end of which is secured a crank 28 which in turn is pivoted to a vertically placed actuator link 29 pivoted on a crank 30 mounted on a rock shaft 31 which in turn is connected to the device by which the function of the holder of the power transmitting 80 mechanism is interrupted and restored. 85

The power transmitting mechanism is the same as that described in the Patent No. 902,103, above referred to.

100 100 indicates the motor and 101 is a shaft moved therefrom and carrying a worm 102 90 in mesh with a worm gear 103 rigidly secured to a shell, 202 so that the gear and shell rotate on an intermediate shaft 105 on which they are loosely mounted.

The coupling mechanism comprises a control ring 113 provided with projecting toes 114 and slots 121. It also comprises a holder consisting of an arm 151 adapted to engage the toes 114 and provided with an arm 153 having a restoring roller 154. A 100 cam 113^a is mounted with the control ring which has depressions 113^b, one of which is opposite roller 154 when the clutch is at rest, allowing the roller 154 and arm 153 to be moved inward to trip the clutch. During the half-revolution of the mechanism, the arm 153 is cammed back to its original position. 105

To the shaft 105 is attached a spider 105^a to which is pivoted at 105^c a pair of friction 110

shoes 105^b adapted to engage the constantly rotating shell 202. Springs 105^a attached to the spider and the shoes tend to effect this engagement. The shoes are kept from 5 contact with the shell by means of the pin and slot connection 121 with the control ring 113. When the ring 113 is released at 114 the springs 105^b contract and the shoes move outwardly until they bear against the 10 shell, which thereupon communicates its motion to the shoes, 105^b, spider 105^a, and shaft 105.

In the operation of the machine, after 15 an item has been enumerated in the usual manner, the actuator bar 21 is depressed by the operator. This moves the link 25 to oscillate the crank 26 and rock the shaft 27 which in turn lowers the crank 28 and actuator link 29 and rocks the shaft 31.

20 This moves the arm 151 to the left, releases the toe 114 with which it has been engaged and permits the constantly rotating motor 100 to be coupled to the intermediate shaft 105 whereby the crank 11 is rotated in the 25 direction indicated by the arrow. The wrist pin 10 therefore reciprocates the slotted link 6 whereby, through the sector 4, the shaft 3 is vibrated. By this time, the arm 153 has performed its function of dis- 30 engaging the motor from the shaft 105 and, through the spring 50, the actuator bar 21 and its connections have been retracted to their original positions and the arm 151 is again restored to its position in the path 35 of the toe 114.

None of the parts above described constitute any part of the present invention. As before stated, this relates to a locking mechanism for the motor actuator and provides 20 means whereby the depression of the actuator bar (21) is prevented before the cycle of operations just described is completed.

The crank 26 is provided with an upwardly extending arm (260) having a slot 45 32 adapted to engage a pin 33 projecting from the frame of the machine and adapted to limit its movement. It also is provided with a laterally projecting flange 34. Loosely mounted to oscillate at a convenient 50 point near the arm 26 and in the form of the device shown surrounding the operative rock shaft 3 is a coöperating locking plate 55 provided with a projecting arm 36 having a lateral flange 37 adapted to coöperate 55 with the flange 34 of the crank 26, and a second projecting arm 38 having an inwardly extending flange 39 adapted to be engaged by the stop foot 5. It is also provided with a slot 40 adapted to engage a pin 41 projecting 60 from the frame 2 of the machine. A spring 43 is adapted to move the arm 38 upward and the arm 36 downward. With these parts mounted on the machine, as the shaft 3 is oscillated the sector 4 is moved 65 with it toward the left and its foot 5 moves

away from the flange 39 of the plate 35 permitting the latter, under the influence of its spring 43, to be moved slightly until the pin 41 contacts with the end of the slot 40. This movement swings the flange 37 into the path of the flange 34 on the crank 26, as shown in Fig. 2, and locks the latter against any movement to the right and obviously, by preventing the movement of the crank 26, prevents any actuation of the actuator bar 21, actuator link 29, or any of their intermediate mechanism. The flanges 37 and 34 remain in this locked position until toward the end of the rearward stroke of the shaft, the foot 5 contacts again with the flange 39 and depresses it to move the plate 35 and flange 37 to an unlocking position, at the same time restretching the spring 43.

The connection between the crank 11 85 mounted on the intermediate shaft 105 and the slotted link 6 need not necessarily be through such a wrist pin and slot. Such connection is convenient to permit of a slipping movement between the motor and the 90 main shaft but except for such convenience a direct pivot connection would be equally as useful and efficient.

What I claim as new is:—

1. In a device of the character described, 95 comprising an operative rock shaft, a continuously running motor, an intermediate shaft, and a motor actuator, by the movement of which the intermediate shaft is temporarily coupled to the motor; means 100 adapted to lock the motor actuator during the major portion of the stroke of the operative rock shaft, consisting of a locking arm moved by the actuator, and a locking plate moved in unison with the operative 105 rock shaft during its stroke and adapted to engage the locking arm.

2. In a device of the character described, comprising an operative rock shaft, a continuously running motor, an intermediate 110 shaft, an operative connection between the operative rock shaft and the intermediate shaft, a clutch mechanism adapted to couple the intermediate shaft to the motor, means adapted to hold such mechanism 115 inactive and means adapted to interrupt the function of the holding mechanism, consisting of a depressible actuator and a train of mechanism embodying an oscillating crank provided with a locking arm; means for locking the arm and the train of mechanism, consisting of a member moving in unison with the operative rock shaft and adapted to engage the locking arm.

3. In a machine of the character described, 125 comprising an operative rock shaft, an oscillating crank provided with a locking arm, an oscillating plate normally held out of engagement with such locking arm and means whereby it is moved into such en- 130

- gagement when the said operative shaft is rocked.
4. In a machine of the character described, comprising an operative rock shaft, an oscillating crank provided with a locking arm, a plate mounted to oscillate in harmony with the operative rock shaft and means normally tending to move the plate into engagement with the locking arm.
- 10 5. In a machine of the character described, comprising an operative rock shaft, an oscillating crank provided with a locking arm, a plate mounted to oscillate in harmony with the operative rock shaft and a spring normally tending to move the plate into engagement with the locking arm.
- 15 6. In a machine of the character described, comprising an operative rock shaft, an oscillating crank provided with a locking arm, a plate mounted to oscillate in harmony with the operative rock shaft and a spring normally tending to move the plate into engagement with the locking arm, and devices detaining it from said engagement actuated from the operative rock shaft.
- 20 7. In a machine of the character described, comprising an operative rock shaft, an oscillating crank provided with a locking arm, a plate mounted to oscillate in harmony with the operative rock shaft and a spring normally tending to move the plate into engagement with the locking arm and devices detaining it from said engagement controlled by the movement of the operative rock shaft.
- 25 8. In a machine of the character described, comprising an operative rock shaft, an oscillating crank provided with a locking arm, a plate mounted to oscillate in harmony with the operative rock shaft and a spring normally tending to move the plate into engagement with the locking arm, and devices detaining it from said engagement, comprising a projection on the plate and a member moved by the operative rock shaft cooperating therewith to hold it inactive.
- 30 9. In a machine of the character described, comprising an operative rock shaft, an oscillating crank provided with a locking arm, a plate mounted to oscillate in harmony with the operative rock shaft and a spring normally tending to move the plate into engagement with the locking arm, and devices detaining it from said engagement, comprising a projecting flange and a member secured to the operative rock shaft and adapted to engage the flange.
- 35 10. In a machine of the character described, comprising an operative rock shaft, an oscillating crank provided with a locking arm, a plate mounted to oscillate in harmony with the operative rock shaft and a spring normally tending to move the plate into engagement with the locking arm, and means whereby its movement is limited.
11. In a machine of the character described, comprising an operative rock shaft, an oscillating crank provided with a locking arm, a plate mounted to oscillate in harmony with the operative rock shaft and a spring normally tending to move the plate into engagement with the locking arm and means whereby its movement is limited, comprising a slot and pin.
- 70 12. In a machine of the character described, comprising an operative rock shaft, an oscillating crank provided with a locking arm, a plate mounted to oscillate in harmony with the operative rock shaft and means on the operative rock shaft adapted to hold the oscillating plate against movement until the shaft is rocked.
- 75 13. In a machine of the character described, comprising an operative rock shaft, an oscillating crank provided with a locking arm, a plate mounted to oscillate in harmony with the operative rock shaft and means on the operative rock shaft adapted to hold the oscillating plate against movement until the shaft is rocked and thereafter to permit it to have a limited movement to engage the locking arm.
- 80 14. In a machine of the character described, comprising operative mechanism, a motor, a connection between the motor and the machine, including an actuator, means for rendering the actuator inoperative after it has performed its function of coupling the motor to the machine and until the movement of the latter is substantially completed, consisting of a latch connected to the actuator, a catch moved toward it by means independent of the motor and operative mechanism of the machine and a device actuated by the operative mechanism to oppose such movement.
- 85 15. In a machine of the character described, comprising operative mechanism, a motor, a connection between the motor and the machine, including an actuator, means for rendering the actuator inoperative after it has performed its function of coupling the motor to the machine and until the movement of the latter is substantially completed, consisting of a latch connected to the actuator, a catch moved toward it by means independent of the motor and operative mechanism of the machine and a device actuated by the operative mechanism to oppose such movement, and restore the catch to an inoperative position when the operative mechanism of the machine has completed its function.
- 90 16. In a machine of the character described, comprising operative mechanism, a motor, a connection between the motor and the machine, including an actuator, means for rendering the actuator inoperative after it has performed its function of coupling the motor to the machine and until the
- 95 100 105 110 115 120 125 130

movement of the latter is substantially completed, consisting of a lock member rigidly secured to the actuator, a coöperating lock member loosely secured to the operative mechanism and means independent of such mechanism tending normally to move the second lock member toward the first.

17. In a machine of the character described, comprising operative mechanism, a motor, a connection between the motor and the machine, including an actuator, means for rendering the actuator inoperative after it has performed its function of coupling the motor to the machine and until the movement of the latter is substantially completed, consisting of a lock member rigidly secured to the actuator, a coöperating lock member loosely secured to the operative mechanism and means independent of such mechanism tending normally to move the second lock member toward the first, and further means actuated from said mechanism adapted to control and reverse such movement.

25 18. In a machine of the character described, comprising operative mechanism, a motor, a connection between the motor and the machine, including an actuator, means for rendering the actuator inoperative after it has performed its function of coupling the motor to the machine and until the movement of the latter is substantially com-

pleted, consisting of a lock member rigidly secured to the actuator, a coöperating lock member loosely secured to the operative mechanism and means independent of such mechanism tending normally to move the second lock member toward the first, in combination with means for limiting the extent of movement of each lock member. 40

19. In a machine of the character described, comprising operative mechanism, a motor, a connection between the motor and the machine, including an actuator, means for rendering the actuator inoperative after it has performed its function of coupling the motor to the machine and until the movement of the latter is substantially completed, consisting of a lock member rigidly secured to the actuator, a coöperating lock member loosely secured to the operative mechanism and means independent of such mechanism tending normally to move the second lock member toward the first, in combination with means for limiting the extent of movement of each lock member, including a detent and slot. 45
